UNITED STATES PATENT OFFICE.

SAMUEL B. STEWART, JR., OF SCHENECTADY, NEW YORK, ASSIGNOR TO
GENERAL ELECTRIC COMPANY, A CORPORATION OF NEW YORK.

CIRCUIT-BREAKER.

SPECIFICATION forming part of Letters Patent No. 744,125, dated November 17, 1903.

Application filed January 23, 1901. Serial No. 44,342. (No model.)

To all whom it may concern:

Be it known that I, SAMUEL B. STEWART, Jr., a citizen of the United States, residing at Schenectady, county of Schenectady, State of New York, have invented certain new and useful Improvements in Circuit-Breakers, of which the following is a specification.

This invention relates to circuit-breakers for currents of large amperage and considerable potential, the object being to provide a device of this character which will be more compact than those hitherto manufactured and which will have all live parts completely inclosed to avoid possibility of shock by contact of operators or others with exposed parts.

The invention is particularly advantageous for use on trolley-cars, its small compass and freedom from danger rendering it desirable for this purpose.

The invention involves mechanical features of construction by which a compact organization is provided and by which the operative parts may be completely housed in a protecting-casing. To these ends I provide two fixed terminals, in operative relation to which is a movable contact pivoted on the same stud as an operating-lever, the handle of which projects outside of the casing. The movable contact is spring-pressed by a helical spring surrounding the stud on which the arm which carries it is pivoted and co-operates with a detent having a sloping shoulder which engages a corresponding shoulder on the supporting-arm. This detent lies at right angles to a latch or lock, and the two are connected by a spring normally in a condition of stress and tending to drop the detent behind the beveled shoulder on the contact-arm, and also to press the latch over a shoulder on the

stud. Secured to the operating-lever is a lug adapted to press back the latch and by a further movement to force the detent out of engagement with the contact-arm. An electromagnetic trip is arranged to similarly actuate the latch and detent. The stud, which supports the pivoted contact-arm, forms an integral part of the core of the blow-out coil, the cover-plate of the casing constituting an extended pole, and an iron casting on the bottom forming another pole. Between the

poles is a blow-out chute, at the inner end of which are placed the circuit-terminals.

The novel features of the invention will be specifically described hereinafter and definitely indicated in the claims appended to this specification.

In the accompanying drawings, which illustrate the invention, Figure 1 is a plan view of a circuit-breaker embodying my improvements. Fig. 2 is a sectional elevation on a plane at right angles to that indicated in Fig. 1. Fig. 3 is a detached view of the operating-lever, handle, and movable contact. Fig. 4 is a detail view of the automatic tripping device.

1 represents a blow-out coil placed in series relation to the contacts 2 2^a. The core of this magnet is secured in a cast-iron plate 3, forming part of the bottom of the casing, the body of which is formed of a box-like casting provided with openings at the ends to permit the movements of the handle and accommodate the insulating-plates 4 4^a, which form the top and bottom walls of the blow-out chute. The cast-metal cover 5 closes the top of the casing. The movable bridging contact 6 is carried on and insulated from an arm 7, pivoted on the stud, which forms a continuation of the core 8 of the blow-out magnet. Around this stud is a helical spring 9, one end of which is anchored in a cap-plate 10, secured to the stud, and the other end in the hub of the pivoted arm 7. The operating-lever is pivoted on the hub of the arm 7, as indicated at 11. This operating-lever and the hub are connected by a helical spring 12, secured to lugs or ears projecting from the respective parts, which spring tends to draw the two parts to a position where coöperating lugs 13 13^a engage one another, and thus prevent the handle from swinging under vibration or rocking of the car and tripping the circuit-breaker. Thus when the operating-handle 14 is moved downwardly and the device occupies the position shown in Fig. 1 the lugs 13 13^a engage and permit the handle to give a positive movement against the tension of spring 9 to the bridging-contact 6, thus forcing the latter into engagement with the terminal contacts 2 2^a and closing the circuit.

When set in this position, the beveled detent 15 drops behind the sloping wall 16, projecting from the movable contact, and at the same time a latch 17, projecting through a hole in the detent, drops over the end wall of the hole under the tension of a spring 18 and positively locks the detent in engagement with the lug 16 on the movable contact. The detent is carried on a lever pivoted on the side of the casing and stands at right angles to the latch 17, the latter having an elbow 17^a, in which the end of the helical spring is connected. Thus the two levers, the detent, and the latch are always drawn toward a locking position by the spring 18, so that immediately on the bridging-contact being shifted to the position where the beveled nose of the detent can drop behind the shoulder 16 the latch 17 falls into place and locks it in that position, where it remains until forced away by the releasing devices. These releasing devices are twofold in character, one being hand-operated and comprising a lug 19, forming a part of the hand operating-lever, which after a determinate range of motion of the handle presses against the latch 17 and raises it from engagement with the wall of the detent. When the parts are well lubricated, this will be sufficient to effect an opening of the circuit; but to make such opening movement perfectly certain I provide an auxiliary lug, (indicated in dotted lines in Fig. 2 at 19^a,) which upon further traverse after the lug 19 has acted forces the detent 15 outwardly and effects a positive disengagement of the coöperating beveled shoulders.

The automatic releasing device comprises an armature 20, pivoted on the cover in a plane to be in proximate relation to the extension of the core 8 of the blow-out magnet. Rigidly connected with the armature is a tongue 21, crossing the plane of the latch and detent at a point within the range of both of them, as indicated in Fig. 1, whereby when the armature is drawn up to the pole of the magnet the tongue 21 first rides over the inclined shoulder 21^a on the latch, thus opening it, and then engages the detent, effecting a positive release in a fashion similar to that already described in connection with the hand-operated releasing device.

The fixed circuit-terminals 2 2^a are at the inner end of a blow-out chute, across which a magnetic field is maintained by the iron cover 5 and the casting 3, which form poles of the blow-out magnet. This chute may be made of any suitable insulating material, such as fiber, and is composed of top and bottom walls 4 4^a and side walls 22 22^a, doweled or otherwise secured to the plates. At the inner end of the chute and in the path of the gases expelled from the arc when the circuit is being broken are arc-ing contacts 23 23^a, formed of copper or other metal, which prevent serious burning of the circuit-breaker contacts. These contacts are fastened in place by bolts, as indi-

cated in Fig. 1, so as to be exchangeable when damaged. Being in contact with the circuit-terminals, when a conductive path is formed between them by the expulsion of the arc gases, the potential at the contacts is reduced, the final opening of the circuit being effected by rupture of the arc-stream at the contacts 23 23^a. In order to effect a better contact, one of the terminals may be provided with an auxiliary contact 24, formed of a bundle of laminæ of phosphor-bronze or other good conductor, screwed fast to the one terminal in a position to be engaged by the bridging-contact 6 when the circuit is closed.

The armature of the magnetic releasing device is controlled by a helical spring 25, attached to a lug 27 on the tongue 21 of the armature, the tension of which may be varied by adjusting screw 26 in a manner well understood in the art and by which the exact point of current strength at which the circuit is to open may be determined.

All parts of the casing are insulated from the circuit-terminals or any live parts of the circuit-breaker, and all parts carrying current are completely housed within the casing, a construction of great advantage in a circuit-breaker designed for use on trolley-cars or other places where the pressure of a crowd renders contact of people with the device possible.

In setting the circuit-breaker a movement of the handle 14 (downwardly in the drawings) brings the lug 13, forming a part of the operating-lever against the lug 13^a and carries the movable contact-arm 7 around against the tension of its operating-spring until the detent 15 engages with the shoulder 16, the latch 17 locking the parts in position. If it becomes desirable for any reason for the motorman to open the circuit by hand, the handle may be moved, (upwardly in the drawings,) thereby shifting the lug 19 and opening the latch and then bringing the lug 19^a against the detent 15 and disengaging it, permitting the energy stored in the spring 9 to throw the bridging-contact 6 rapidly away from the contact 2 with a snapping action, drawing an arc which is instantly ruptured by the magnetic field enclosing the contacts. The bridging-contact when tripped has independent motion sufficient in range to safely open the circuit whether the operator holds the handle or not.

In case of an overload on the circuit in which the circuit-breaker is connected the armature 20 is drawn down against the tension of spring 25 and brings the arm 21 against the inclined shoulder on the latch, thereby raising the latter and then forcing outwardly the detent, thus releasing the movable contact and permitting the circuit to open, as above described.

What I claim as new, and desire to secure by Letters Patent of the United States, is—

1. A circuit-breaker comprising fixed and movable contacts, an operating-lever, the

movable contact and operating-lever being independently pivoted at the same point, a spring independent of the operating-lever governing the movable contact and adapted to be strained by said lever, and a detent for the spring adapted to be released by the lever, the lever and movable contact having sufficient lost motion to open the circuit independently of the lever motion when the detent is released.

2. A circuit-breaker comprising two fixed contacts, a movable bridging contact, an arm carrying the same from which it is insulated, an operating-lever, both arm and lever being pivoted on the same stud, a spring independent of the operating-lever surrounding the stud and controlling the contact-arm, a detent for locking the arm in a closed position, and a releasing device operated by said lever.

3. A circuit-breaker comprising a movable contact and operating-lever, both independently pivoted on the same stud, a spring connecting them, coöperating lugs permitting them to be moved as a unit in one direction, a spring engaging the movable contact, a detent for holding it in closed position, a latch at an angle to the detent to lock it in closed position, and a spring connecting the latch and detent impelling them in a direction to

lock the movable contact when it reaches a closed position.

4. A circuit-breaker comprising a spring-actuated contact, an operating-handle for compressing the spring, a detent for holding the circuit closed, a latch for locking the detent, a tripping-lug carried by the operating-lever for opening the latch, and an auxiliary lug for disengaging the detent.

5. A circuit-breaker comprising a spring-actuated contact, an operating-handle for compressing the spring, a detent for holding the circuit closed, provided with a beveled engaging tip, a latch for locking the detent, and two tripping-lugs on the operating-lever operating in sequence, one to trip the latch and the other the detent.

6. A circuit-breaker comprising a blow-out magnet, a movable contact and operating-lever journaled on an axis in prolongation of the magnet-core, a controlling-spring, detent and releasing devices for tripping the circuit-breaker.

In witness whereof I have hereunto set my hand this 21st day of January, 1901.
